UNITED STATES PATENT OFFICE

116,698

DESIGN FOR A COMBINED TEMPERATURE AND ALTITUDE GAUGE FOR STEAM BOILERS

George F. Ruopp, Marshalltown, Iowa

Application April 22, 1939, Serial No. 84,495

Term of patent 7 years

To all whom it may concern:

Be it known that I, George F. Ruopp, a citizen of the United States, residing at Marshalltown, in the county of Marshall and State of Iowa, have invented a new, original, and ornamental Design for a Combined Temperature and Altitude Gauge for Steam Boilers, of which the following is a specification, reference being had to the accompanying drawing, forming part thereof.

Figure 1 is a front elevation of the combined temperature and altitude gauge for steam boilers showing my new design;

Figure 2 is a side elevation; and

Figure 3 is a rear elevation.

I claim:

The ornamental design for a combined temperature and altitude gauge for steam boilers, as shown.

GEORGE F. RUOPP.
